CLAIM

The ornamental design for a extension for a light switch actuator, as shown and described.

DESCRIPTION

FIG. 1 is a perspective view of the extension for a light switch actuator showing my new design;

FIG. 2 is a front elevation view thereof;

FIG. 3 is a side elevation view thereof, the other side being a mirror image thereof;

FIG. 4 is a top plan view thereof;

FIG. 5 is a bottom view thereof; and,

FIG. 6 is a rear elevation view thereof.
